FIG. 5 8 5

Inventor:

Charles D. Winsfield,

By Geo. A. Byrd.

Attorney.

UNITED STATES PATENT OFFICE.

CHARLES DOUGLAS WINFIELD, OF BROOKLYN, NEW YORK.

FOLDING COT.

1,398,758.

Specification of Letters Patent. Patented Nov. 29, 1921.

Application filed September 18, 1920. Serial No. 411,199.

To all whom it may concern:

Be it known that I, CHARLES DOUGLAS WINFIELD, a citizen of the United States, and resident of Brooklyn, in the county of 5 Kings and State of New York, have invented certain new and useful Improvements in Folding Cots, of which the following is a specification.

This invention relates to folding cots principally adapted for use in sleeping out of doors and has for its object to provide a cot of this character adapted to be readily folded into small compass to facilitate storage and transportation.

15 Another object of the invention is to provide a relatively simple and inexpensive cot of this character which shall be easy to set up and be found strong and durable when in use.

20 With these and other objects in view the invention consists of certain novel constructions, combinations and arrangements of parts as will be hereinafter more fully described and particularly pointed out in 25 the appended claims.

Referring to the drawings forming a part of this specification in which like numerals designate like parts in all the views—

Figure 1 is a perspective view of the invention shown set up and ready for use.

Fig. 2 is a side elevational view with parts shown broken away for clearness.

Fig. 3 is a fragmentary perspective view of the head portion of the cot showing the 35 method of securing the pillow thereto.

Fig. 4 is a side elevational view of the head portion showing the same in a partially folded position.

Fig. 5 is a fragmentary perspective view 40 of the foot portion of the cot showing the stretcher or body portion removed therefrom.

Fig. 6 is a fragmentary side elevational view of the foot portion of the cot showing 45 a modified form of supporting means, and

Fig. 7 is a fragmentary side elevational view of a modified form of the head portion of the cot.

50 Referring to the drawings in detail 1—1 designates the side rails of the main frame of the cot, suitably spaced and connected by the cross bars or rungs, 2—2, and 3—3 which designate the legs arranged in pairs in the usual manner for supporting the frame when in use.

The legs are pivotally connected as at 4—4 to the inner side portions of the rails adjacent the ends thereof and are arranged when in their outer or extended position to 60 engage the cross bars 2—2 to support the frame in its proper spaced relation from the ground.

A body supporting portion 5 preferably formed of canvas is best adapted for cots 65 of this type. This portion is detachable from the frame and is herein shown in the form of a stretcher, comprising the main canvas portion 6 having its side edges formed into loops 7 for receiving the detachable rods 8. These rods are made slightly longer than the canvas portion so that they may extend beyond its ends to provide handle or gripping portions for carrying the stretcher when detached from the frame and 75 for connecting the stretcher to the frame for use as a cot. Any suitable means may be provided for quickly and conveniently detaching and attaching the stretcher to the frame such as for example by providing the 80 side rails, adjacent the ends thereof, with movable sockets 9 in which the handle portions of the stretcher are adapted to fit. As shown these sockets are formed of strips of canvas formed into loops and have their 85 ends suitably secured to the under side portions of the side rails 1—1. By forming these sockets of canvas and connecting them to the rails so as to engage the outer side portions as shown it is obvious that the 90 loops may be easily manipulated for removing and replacing the stretcher when desired.

In cots of this type it is desirable that the user be made as comfortable as possible, such 95 as being protected by an awning or canopy top from the hot rays of the sun. The awning or canopy top designated at 10 is supported in suitable spaced relation from the main frame by the arms 11 which are pivotally connected at their lower ends as at 12 to the side rails 1—1 adjacent one end thereof. The arms are located at the head portion of the cot and have pivotally connected to their upper ends, the frame 13 of 105 the canopy. The frame may be made of any suitable material, is preferably rectangular in shape and is covered with a light and durable canvas. Adjacent one end the frame is provided with a rung or cross piece 14 110 which extends beyond each side of the frame, for connecting it to the upper ends

of the arms 11. By providing the upper end of one of the arms 11, as shown in Fig. 3, with a forked bearing portion into which one of the extended ends of the rung 14 fits 5 it is obvious that the canopy may be removed from the cot frame where desired, by slightly raising that side of the canopy frame to step the end of the rung from the forked bearing and then laterally withdraw- 10 ing the other end of the rung from the bearing in the arm on the opposite side.

To normally maintain the canopy in any adjusted position a means herein shown in the form of a coil spring 16 is provided. 15 This spring is located intermediate the pivotal and the end portion of the canopy frame and has one of its ends connected to the central portion of a rung or cross piece 17 mounted on the canopy frame and the 20 other of its ends detachably connected to a hook 18 secured to the central portion of the cross bar 2 at the head portion of the cot frame. Side braces 20—20, shown in the form of strips of canvas, having one of 25 their ends connected to the side rails and the other of their ends connected to the arm 11 are provided for limiting the movement of the arms in one direction whereby they may be maintained rigidly in their upper position 30 with sufficient strength to support the weight of the canopy and the head of an occupant when the pillow with which the cot is provided, is used.

Actual experience has proven that by pivotally connecting the canopy frame adjacent one end, to a pair of upright arms on the cot frame and connecting a coil spring to the cot and canopy frames behind the pivot connection the canopy is properly counter- 40 balanced so that it may be held in any adjusted position when desired. To obviate any liability of the canopy becoming accidentally displaced upwardly after being adjusted or to secure the same in a permanent 45 adjusted position and prevent the wind from blowing the same upwardly, a rope 21 may be provided, one end of which may be secured to the end of the canopy frame and the other end secured to the foot sec- 50 tion of the cot.

To further provide for the comfort of a user the cot may also be provided with a pillow 22, preferably formed from a piece of canvas and suitably reinforced along its 55 edges. To secure the pillow in position to the head portion of the cot as clearly shown in Fig. 3 any suitable attaching and detaching means may be employed, such as for instance by providing the corners of the pil- 60 lows with openings 23 adapted to engage the headed projections or buttons 24 secured to the sides of the main frame and the arms 11 near the upper ends thereof.

As shown in Fig. 6 the cot may be 65 equipped with wheels if desired. The

wheels designated at 25 have their axles 26 mounted in bearings secured to the outer edge portions of the legs and are arranged so that when the legs are folded the axles will bear against the under side of the side 70 rails and the cot supported on the wheels for wheeling from place to place when desired. When the legs are unfolded the cot may be supported thereby and the wheels held out of contact with the ground. 75

As shown in Fig. 7 the legs 3^a are pivotally connected to the side rails 1 and are provided with a rearwardly extending portion 3^b which engages the under portion of the side rails to support the frame when the 80 legs are extended. The arms 11^a are also provided with a rearwardly extending portion 11^b which engages the upper portion of the side rails to brace the arms when they are raised to their upper or extended position. 85

It is obvious that those skilled in the art may vary the details of construction and combination and arrangement of parts without departing from the spirit of my invention, and therefore, I do not wish to be limited to such features except as may be required by the claims. 90

What I claim is—

1. In a cot of the character described the 95 combination with a frame of a pair of upright arms pivotally connected at their lower ends to the head portion of the frame, braces connecting said arms and frame, an adjustable canopy pivotally and detachably connected to the upper ends of said arms, resilient means located intermediate the pivotal and the end portion of the canopy and connecting said frame and canopy for yieldably holding said canopy in an ad- 100 justed position and means connecting the canopy and frame for adjusting the canopy and for preventing its accidental upward displacement. 105

2. In a cot of the character described the 110 combination with a frame of a pair of upright arms pivotally connected at the lower ends to the head portion of the frame, canvas braces connecting said arms and frame, an adjustable canopy pivotally and detach- 115 ably connected to the upper ends of said arms, a coil spring located intermediate the pivotal and the end portion of the canopy having one end connected to said frame and the other end connected to said canopy for yieldably holding said canopy in an adjust- 120 ed position and means connecting the canopy and frame for adjusting the canopy and preventing its accidental upward displacement. 125

Signed at New York, in the county of New York and State of New York, this 8th day of September, A. D. 1920.

CHARLES DOUGLAS WINFIELD.
